SEPARATION OF ALKYL AROMATIC HYDROCARBONS WITH AN ALUMINUM HALIDE AND A GROUP I OR II METAL HALIDE

Carleton B. Scott, Pomona, William D. Schaeffer, Berkeley, and John D. Wordie, Fullerton, Calif., assignors to Union Oil Company of California, Los Angeles, Calif., a corporation of California

Application March 22, 1954, Serial No. 417,930

18 Claims. (Cl. 260—674)

This invention relates to a method for separating aromatic hydrocarbons, and in particular concerns a method for separating one or more specific isomers from isomeric mixtures of dialkylbenzenes, e. g. xylenes.

Certain aromatic hydrocarbon compounds, particularly the lower dialkylbenzenes, are ordinarily obtained in the form of isomeric mixtures from which the individual isomers cannot be separated by conventional fractional distillation procedures. For example, the C₈ fraction obtained in petroleum hydrocarbon reforming operations contains ortho-, meta, and para-xylenes and ethylbenzene, all of which have boiling points within about 8° C. of each other. Two of the isomers, meta- and para-xylenes, boil within about 0.8° C. of each other. Various methods have been proposed for resolving isomeric mixtures of this type, e. g., fractional crystallization and selective chemical reaction, but none of such methods has proved entirely satisfactory for large-scale operation.

It is accordingly an object of the present invention to provide an improved method for resolving mixtures comprising isomeric lower dialkylbenzenes.

Another object is to provide a commercially attractive method for the separation of mixed xylenes.

A further object is to provide an improved method for separating individual isomers from the C₈ fraction of petroleum hydrocarbon reformates.

Other and related objects will be apparent from the following detailed description of the invention, and various advantages not specifically referred to herein will occur to those skilled in the art upon employment of the invention in practice.

We have found that the foregoing objects and attendant advantages may be realized in a process which comprises treating the isomeric mixture with an aluminum halide and certain other metallic halides. More particularly, we have found that the addition of an aluminum halide and a halide of a metal of group I or II of the periodic system to hydrocarbon mixtures comprising isomeric lower dialkylbenzenes results in the formation of a liquid complex comprising the metallic halides and one particular hydrocarbon isomer. When the isomeric mixture comprises mixed xylenes, the complex is formed with the meta isomer. In some instances the liquid complex is substantially immiscible with the non-complexed isomers, and may be separated therefrom by simple settling and decantation. Alternatively, the non-complexed isomers may be separated from the complex by selective solvent extraction with a liquid aliphatic hydrocarbon such as pentane, hexane, heptane, iso-octane, decane, etc. In its simplest embodiment the invention thus comprises the steps of adding an aluminum halide and one of the aforementioned metal halides to a mixture of lower dialkylbenzene isomers, whereby one of said isomers is selectively complexed with the metallic halides, and thereafter separating the complex from the non-complexed isomers. The complex may be treated directly to recover the selectively complexed isomers therefrom, or as is hereinafter more fully explained it may be employed directly in a process

2

adapted to produce either of the non-complexed isomers as the ultimate product.

For convenience, the invention is herein described as it is applied to the treatment of various mixtures comprising mixed xylenes, but it is to be understood that the principle of the invention may be similarly applied to the treatment of any hydrocarbon mixture comprising lower dialkylbenzenes. The term "lower dialkylbenzene" is herein employed to designate dialkylbenzenes in which each alkyl group contains from 1 to 4 carbon atoms, and thus includes within its scope xylenes, di-ethylbenzenes, di-n-propylbenzenes, di-n-butylbenzenes, butyltoluenes, cymenes, ethyl-cumenes, tert-butyl-ethylbenzenes, etc.

The following examples will illustrate practice of the invention in its simplest form, but are not to be construed as limiting the same.

Example I

Approximately 40 parts by weight (3 moles) of anhydrous aluminum chloride is added to about 53.5 parts by weight (5 moles) of a mixture comprising the three xylene isomers and ethylbenzene. The aluminum chloride does not dissolve in the hydrocarbon mixture, but remains at the bottom of the vessel as a separate solid phase. Approximately 12.7 parts by weight (3 moles) of lithium chloride is then added to the two-phase mixture. Upon shaking, the metal halides dissolve in the hydrocarbon phase with the evolution of heat to form a brown liquid. This product is then extracted with n-heptane, and the extract phase is poured into ice water to hydrolyze any aluminum chloride which might be present. However, the absence of any appreciable amount of aluminum hydroxide in the hydrolyzed extract indicates that substantially none of the aluminum chloride is in the extract phase. The raffinate, i. e., the product not removed by the extraction with heptane, is also poured into ice water. The hydrocarbon portion of each of the two hydrolysis products is then analyzed for individual xylene isomers and ethylbenzene, with the following results being obtained:

Sample	p-Xylene, percent	m-Xylene, percent	o-Xylene, percent	Ethylbenzene, percent	Ratio, m/p
Feed Mixture.....	21.8	49.8	14.2	14.2	2.28
Hydrolyzed Extract.....	23.2	44.2	15.2	17.4	1.86
Hydrolyzed Raffinate.....	21.2	53.4	15.1	10.3	2.52

Example II

The procedure of Example I is repeated, employing 16.5 parts (1.5 mole) of cuprous chloride in place of the lithium chloride. During solution of the cuprous chloride in the hydrocarbon-aluminum mixture artificial cooling is supplied to prevent the temperature from exceeding about 25° C. The following analytical results are obtained:

Sample	p-Xylene, percent	m-Xylene, percent	o-Xylene, percent	Ethylbenzene, percent	Ratio, m/p
Feed Mixture.....	22.3	49.5	13.7	14.5	2.22
Hydrolyzed Extract.....	23.6	38.8	9.7	22.9	1.36
Hydrolyzed Raffinate.....	25.0	55.8	10.9	8.3	2.22

Example III

Approximately 3 moles of aluminum bromide and 1.5 moles of potassium bromide are shaken with 3 moles of a mixture of xylenes and ethylbenzene at a temperature of about 100° C. The resulting mixture is extracted with

n-heptane and the extract and raffinate phases were hydrolyzed as in Example I. The following analytical results were obtained:

Sample	p-Xylene, percent	m-Xylene, percent	o-Xylene, percent	Ethylbenzene, percent	Ratio, m/p
Feed Mixture	22.3	49.5	13.7	14.5	2.22
Hydrolyzed Extract	22.7	49.0	13.7	14.6	2.16
Hydrolyzed Raffinate	19.9	57.9	10.3	11.9	2.81

Similar results are obtained when aluminum chloride and sodium chloride are employed.

Example IV

The procedure of Example I is repeated, employing 2 moles of aluminum chloride and 0.4 mole of mercuric chloride per mole of hydrocarbon and a somewhat different feed composition. The following results are obtained:

Sample	p-Xylene, percent	m-Xylene, percent	o-Xylene, percent	Ratio, m/p
Feed Mixture	53.7	46.1	0.2	0.86
Hydrolyzed Extract	63.9	34.3	1.8	0.54
Hydrolyzed Raffinate	45.8	51.9	2.3	1.10

Example V

A xylene mixture containing 54 percent by volume of para-xylene and 46 percent by volume of meta-xylene (ratio, m/p=0.85) is treated with one molecular equivalent of aluminum chloride and 0.16 molecular equivalent of cadmium chloride, and the resulting mixture is extracted with n-heptane as in Example I. The extract and raffinate phases are hydrolyzed with ice water, and the hydrocarbon phases of the hydrolysate are found to contain:

	Hydrolyzed Extract, Percent by Vol.	Hydrolyzed Raffinate, Percent by Vol.
m-Xylene	25.5	65.2
p-Xylene	71.9	27.0
o-Xylene	2.6	7.8
Ratio, m/p	0.34	2.42

The small amount of ortho-xylene formed is due to the isomerizing influence of the metal halides and can be reduced by operating at a lower temperature. When 0.2 molecular equivalent of mercurous chloride is substituted for the cadmium chloride the ratio of meta-to-para is 0.35 in the hydrolyzed extract and 1.58 in the hydrolyzed raffinate.

The aluminum halide which is employed in accordance with the invention is anhydrous aluminum chloride, bromide or iodide, and the other metallic halide is a chloride, bromide or iodide of one of the metals of groups I or II of the periodic system, e. g., sodium chloride, potassium bromide, lithium chloride, calcium iodide, magnesium chloride, cadmium bromide, mercuric iodide, beryllium chloride, barium bromide, gold chloride, cupric iodide, strontium chloride, etc. Ammonium halides are also operable, and the ammonium ion is herein considered as a group I metal. Of these metal halides, the chlorides are preferred by reason of their lower cost and general availability. It is not necessary that the halogen atom be the same, i. e., aluminum chloride may be employed with sodium bromide or potassium iodide, aluminum bromide may be employed with cadmium chloride, etc.

The amount of aluminum halide employed depends upon the proportion of the selectively complexed isomer in the mixture being treated and upon the degree of selectivity desired. On a molar basis, such amount is usually between about 0.5/1 and about 5/1. Thus, in

treating a mixture of isomeric xylenes containing 50 percent of the meta isomer, the aluminum halide will be employed in an amount representing between about 0.25 and about 2.5 moles per mole of the isomeric mixture.

The metal halide other than the aluminum halide is employed in an amount sufficient to promote solution of substantially all of the aluminum halide in the hydrocarbon mixture. Such amount is usually between about 0.2 and about 1.5 moles of metal halide per mole of aluminum halide.

The treatment of isomeric mixtures with metal halides in accordance with the invention is preferably effected at atmospheric temperatures and/or pressures, although if desired somewhat elevated temperatures and/or pressures may be employed. However, since the metal halides promote isomerization at elevated temperatures, the temperature should be controlled so as not to exceed the temperature at which substantial isomerization occurs. In general, the temperature should be maintained below about 70° C.

As will be apparent to those skilled in the art, the operation may be carried out batch-wise, semi-continuously or continuously by any of the conventional means for contacting solids and liquids. The following example illustrates one form which a continuous process may take:

Example VI

A recycle stream comprising C₈ hydrocarbons rich in meta-xylene, aluminum chloride and cadmium chloride is continuously admixed with a feed stream consisting of a C₈ petroleum hydrocarbon reformate cut of the following composition:

	Percent by volume
p-Xylene	26.5
m-Xylene	45.9
o-Xylene	15.3
Ethylbenzene	12.3
	100.0

The mole ratios of aluminum chloride and cadmium chloride to meta-xylene are about 2/1 and 1/1, respectively. Solution of the feed stream in the recycle stream is effected, and the solution is passed to a continuous multi-stage liquid-liquid extraction column wherein it passes countercurrent to a stream of n-decane. The extract phase is passed to a distillation column wherein an overhead stream comprising C₈ aromatic hydrocarbons lean in meta-xylene is taken off, and a bottoms stream comprising n-decane is returned to the extraction column. The raffinate phase is passed from the extraction column to a continuous vacuum distillation column operating at 20-100 mm. pressure. This column is operated to produce an overhead stream comprising meta-xylene in an amount substantially equal to the meta-xylene content of the feed stream and a bottoms fraction comprising C₈ hydrocarbons rich in meta-xylene, aluminum chloride and cadmium chloride. Said bottoms fraction constitutes the aforesaid recycle stream, and is continuously returned to the initial step of the operation for admixing with a further quantity of the feed.

In the foregoing example, the complexed and non-complexed hydrocarbons are separated by selective solvent extraction. Relatively low-boiling aliphatic hydrocarbons, e. g., hexane, heptane, octane, etc., are preferred solvents for this purpose by reason of their low cost and ready availability, but any solvent which is selective with respect to the complexed and the non-complexed hydrocarbons may be employed. Any of the conventional techniques generally applied to selective solvent extraction processes may be employed. In some instances, depending upon the nature of the isomeric feed mixture and the amount of metal halides employed, the complex is immiscible with the non-complexed hydrocarbons, and the separation of the two may be effected simply by allowing

the mixture to settle followed by mechanical separation of the two liquid phases.

As will be apparent to those skilled in the art, the process of the invention may be carried out in a plurality of stages arranged in cascade fashion. Thus, the raffinate from an initial separation stage may be passed to a second separation stage wherein it is re-treated with the metal halides to obtain a secondary raffinate and a secondary extract. The latter may be recycled back to the initial stage, and the raffinate may be passed to a tertiary stage and again treated with the metal halides. By providing an appropriate number of stages and feeding the raffinate from each stage to the next succeeding stage while returning the extract from each stage to the feed stream of each preceding stage, isomers of any desired degree of purity may be separated from the feed mixture.

The principle of the invention may be applied in various ways to provide a number of integrated processes adapted to the production of substantially pure isomeric hydrocarbons. For example, a mixture of ortho-, meta- and para-xlyenes may be treated as hereinabove explained to obtain substantially pure meta-xylene and a mixture of the ortho and para isomers. The latter mixture may then be fractionally distilled to obtain substantially pure para-xylene as an overhead product and substantially pure ortho-xylene as distillation bottoms. Alternatively, the ortho and para mixture may be separated by fractional crystallization or by selective chemical reaction.

The process of the invention may also be carried out as a combination separation-isomerization process to produce any one of the isomers as the major product. As previously stated, the mixed metal halides of the present class promote the isomerization of lower dialkylbenzenes at temperatures in excess of about 80° C. Accordingly, a mixture of ortho-, meta- and para-xlyenes may be treated with an aluminum halide and a halide of a metal of group I or II of the periodic system at a non-isomerizing temperature, e. g., 30°-50° C., as hereinabove described to obtain the ortho and para isomers in non-complexed form and the meta isomer in the form of a complex with the metal halides. The complex is then directly subjected to isomerizing temperatures, e. g., 80°-150° C. or higher, whereby the meta isomer is isomerized to form an equilibrium mixture of ortho-, meta- and para-xlyenes. Said mixture is then recycled back to the initial separation operation whereby a further quantity of the ortho-para mixture and a further quantity of the complexed meta isomer is obtained.

The following examples will illustrate the use of the metal halides of the present class as isomerization catalysts, but are not to be construed as limiting the invention:

Example VII

A mixture of ortho-, meta- and para-xylene is treated with aluminum bromide and sodium chloride and is extracted with n-decane as above explained, while maintaining a temperature of about 40° C. The hydrocarbon component of the raffinate phase comprises about 90.5 percent by volume of meta-xylene, 8.8 percent by volume of para-xylene and 0.7 percent of ortho xylene. The raffinate, which contains about 0.4 mole each of aluminum bromide and sodium chloride per mole of hydrocarbons, is then heated at a temperature of about 140° C. for a period of about two hours, after which the product is distilled to separate the isomerized hydrocarbons from the metal halides. The distilled product comprises 73.0 percent by volume of meta-xylene, 17.5 percent by volume of para-xylene and 9.5 percent by volume of ortho-xylene. When aluminum bromide alone is employed as the isomerization catalyst, 45.8 percent of the xylenes are dealkylated to benzene and toluene, and the volume recovery is only 23 percent.

Example VIII

A mixture of ortho-, meta- and para-xylene is treated with aluminum bromide and sodium chloride and is ex-

tracted with n-heptane as previously explained. The extract phase, comprising the heptane solvent and a xylene mixture lean in the meta isomer, is fractionally distilled to obtain an overhead fraction comprising the heptane solvent, an intermediate fraction rich in para-xylene, and a bottoms fraction having the following composition:

	Percent by volume
o-Xylene	97.6
m-Xylene	1.9
p-Xylene	0.5
	100.0

The bottoms fraction is admixed with 0.3 molecular equivalents each of aluminum bromide and sodium chloride, and the mixture is heated at 80°-90° C. for 1.5 hours. After filtering to remove the metal salts the isomerized product is found to contain:

	Percent by volume
o-Xylene	46.6
m-Xylene	40.7
p-Xylene	8.3
Benzene	0.2
Toluene	2.3
Residue	1.9
	100.0

This product is treated, as by fractional crystallization, to separate the para-xylene therefrom, and the remainder is recycled to the separation step for removal of the meta-xylene. By repeating this procedure meta- and para-xlyenes are obtained as substantially the sole products. If desired, the meta and ortho isomer streams may be combined prior to the isomerization step, whereby para-xylene is obtained as substantially the sole product.

The drawing which accompanies and constitutes a part of this application is in the form of a flowsheet illustrating several ways of practicing the process of the invention. In said drawing, Figure 1 illustrates the simplest embodiment of the invention wherein the complexed m-xylene is separated from its non-complexed isomers by simple phase separation or, alternatively, by extraction with a suitable solvent, followed by decomposition of the complex to obtain free m-xylene. When solvent extraction is employed the extract is distilled or otherwise treated to separate the solvent, and the latter is recycled to the extraction step. Figure 2 illustrates a more complex embodiment wherein the m-xylene complex is separated from the non-complexed isomers by solvent extraction and is decomposed to obtain free m-xylene, and the extract consisting of solvent and non-complexed xylene isomers is isomerized, with the isomerizate being separated from the solvent and recycled back to the initial step of the process wherein the isomeric mixture is admixed with the complexing agent.

Other modes of applying the principle of our invention may be employed instead of those explained, change being made as regards the methods or materials employed provided the step or steps stated by any of the following claims, or the equivalent of such stated step or steps, be employed.

We, therefore, particularly point out and distinctly claim as our invention:

1. The method of treating an aromatic hydrocarbon mixture comprising meta-xylene and at least one other xylene isomer which comprises adding to said mixture an aluminum halide selected from the class consisting of aluminum chloride, aluminum bromide and aluminum iodide and sufficient of a metal halide selected from the class consisting of the chlorides, bromides and iodides of the metals of groups I and II of the periodic system to cause said aluminum halide to dissolve in said aromatic hydrocarbon mixture while maintaining a tem-

perature below that at which isomerization of said dialkylbenzenes occurs to any substantial extent, and thereafter separating from the mixture so treated a complex comprising the metallic halides and at least one of said dialkylbenzene isomers, the ratio of isomers in said complex being substantially different from the ratio of isomers in said aromatic hydrocarbon mixture.

2. The method of claim 1 wherein said aromatic hydrocarbon mixture comprises the C₈ fraction of a petroleum hydrocarbon reformate and contains meta-xylene, ortho-xylene, para-xylene, and ethylbenzene.

3. The method of claim 1 wherein said aluminum halide is aluminum chloride.

4. The method of claim 1 wherein said aluminum halide is aluminum chloride and said metal halide is cadmium chloride.

5. The method of treating an aromatic hydrocarbon mixture comprising meta-xylene and at least one other xylene isomer which comprises adding to said mixture an aluminum halide selected from the class consisting of aluminum chloride, aluminum bromide and aluminum iodide and sufficient of a metal halide selected from the class consisting of the chlorides, bromides and iodides of the metals of groups I and II of the periodic system to cause said aluminum halide to dissolve in said aromatic hydrocarbon mixture while maintaining a temperature below about 70° C., and thereafter separating from the mixture so treated a liquid complex comprising the metallic halides and at least one of said xylene isomers, the ratio of xylene isomers in said complex being substantially different from the ratio of isomers in said aromatic hydrocarbon mixture.

6. The method of claim 5 wherein said aluminum halide is aluminum chloride.

7. The method of claim 5 wherein between about 0.5 and about 5 moles of aluminum halide are employed per mole of the isomer which forms the said complex.

8. The method of claim 5 wherein the aromatic hydrocarbon mixture is an equilibrium mixture comprising ortho-, meta- and para-xylenes and ethylbenzene.

9. The method of claim 5 wherein between about 0.2 and about 1.5 moles of the said metal halide is employed per mole of aluminum halide.

10. The method of treating an aromatic hydrocarbon mixture comprising meta-xylene and at least one other xylene isomer which comprises adding to said mixture an aluminum halide selected from the class consisting of aluminum chloride, aluminum bromide and aluminum iodide and sufficient of a metal halide selected from the class consisting of the chlorides, bromides and iodides of the metals of groups I and II of the periodic system to cause aluminum halide to dissolve in said aromatic hydrocarbon mixture, subjecting the resulting mixture to selective solvent extraction with a liquid saturated aliphatic hydrocarbon at a temperature below that at which isomerization of said isomeric xylenes occurs to any substantial extent, and separating a raffinate phase comprising a complex containing the metallic halides and at least one isomer of xylene from an extract phase comprising said aliphatic hydrocarbon and non-complexed xylene isomers, the ratio of xylene isomers in the raffinate phase being substantially different from the ratio of xylene isomers in said aromatic hydrocarbon mixture.

11. The method of claim 10 wherein the aluminum halide is aluminum chloride.

12. The method of claim 10 wherein between about 0.5 and about 5 moles of aluminum chloride are employed per mole of that isomer which forms the said complex with metallic halides and between about 0.25 and about 1.5 moles of metal halide are employed per mole of aluminum chloride.

13. The method of claim 10 wherein the temperature is maintained below about 70° C.

14. The method of treating an aromatic hydrocarbon mixture comprising meta-xylene and at least one other

xylene isomer which comprises adding to said mixture an aluminum halide selected from the class consisting of aluminum chloride, aluminum bromide and aluminum iodide and sufficient of a metal halide selected from the class consisting of the chlorides, bromides and iodides of the metals of groups I and II of the periodic system to cause aluminum halide to dissolve in said aromatic hydrocarbon mixture; subjecting the resulting mixture to selective solvent extraction with a liquid saturated aliphatic hydrocarbon at a temperature below that at which isomerization of said isomeric xylenes occurs to any substantial extent; separating a raffinate phase comprising a complex containing the metallic halides and at least one isomer of xylene from an extract phase comprising said aliphatic hydrocarbon and non-complexed xylene isomers, the ratio of xylene isomers in the raffinate phase being substantially different from the ratio of xylene isomers in said aromatic hydrocarbon mixture; recovering the non-complexed isomers from said extract phase; and recovering the complexed isomers from the raffinate phase.

15. The method of claim 14 wherein the said aromatic hydrocarbon mixture comprises ortho-, meta- and para-xylenes and ethylbenzene.

16. The method of treating an aromatic hydrocarbon mixture comprising meta-xylene and at least one other xylene isomer which comprises adding to said mixture an aluminum halide selected from the class consisting of aluminum chloride, aluminum bromide and aluminum iodide and sufficient of a metal halide selected from the class consisting of the chlorides, bromides and iodides of the metals of groups I and II of the periodic system to cause aluminum halide to dissolve in said aromatic hydrocarbon mixture; subjecting the resulting mixture to selective solvent extraction with a liquid saturated aliphatic hydrocarbon at a temperature below that at which isomerization of said isomeric xylenes occurs to any substantial extent; separating a raffinate phase comprising a complex containing the metallic halides and at least one isomer of xylene from an extract phase comprising said aliphatic hydrocarbon and non-complexed xylene isomers, the ratio of xylene isomers in the raffinate phase being substantially different from the ratio of xylene isomers in said aromatic hydrocarbon mixture; and subjecting said raffinate phase to an isomerizing temperature above about 70° C.

17. The method of treating a mixture comprising isomeric xylenes including meta-xylene which comprises (1) adding to said mixture between about 0.5 and about 5 moles of aluminum chloride per mole of meta-xylene and between about 0.25 and about 1.5 moles of a metal halide selected from the class consisting of the chlorides, bromides and iodides of the metals of groups I and II of the periodic system per mole of aluminum chloride while maintaining a temperature below about 70° C.; (2) extracting the resulting mixture with a liquid saturated aliphatic hydrocarbon while maintaining a temperature below about 70° C.; (3) separating a raffinate phase comprising a complex containing the metallic halides and meta-xylene from an extract phase rich in xylene isomers other than meta-xylene, the ratio of isomers in the raffinate phase differing substantially from the ratio of isomers in the extract phase; (4) recovering xylene isomers from said extract phase; (5) subjecting said raffinate phase to an isomerizing temperature above about 70° C.; and (6) returning the isomerized product to step (1).

18. The method of claim 17 wherein the original mixture comprises ortho-, meta- and para-xylenes and ethylbenzene.
